C. Brown & Co.

UNITED STATES PATENT OFFICE.

JOHN F. VENNER, OF BROWNSVILLE, OREGON.

VEHICLE-PROPELLER.

SPECIFICATION forming part of Letters Patent No. 614,907, dated November 29, 1898.

Application filed February 21, 1898. Serial No. 671,183. (No model.)

To all whom it may concern:

Be it known that I, JOHN F. VENNER, a citizen of the United States, residing at Browns-
ville, in the county of Linn and State of Ore-
gon, have invented a new and useful Vehicle-
Propeller, of which the following is a speci-
fication.

My invention relates to a vehicle-propeller adapted for use in connection with road-
wagons, sleds, and similar vehicles, and has
for its object to provide a propeller which
may be efficient in soft soils, particularly in
traversing grades and for use in snow and on
ice, the propeller consisting of a rimless wheel
adapted to be driven by suitable motive power
and capable of sinking into snow or other soft
surfaces in order to attain an efficient hold,
and also capable of engaging hard slippery
surfaces, such as ice, to secure the maximum
efficiency of the motor.

Further objects and advantages of this in-
vention will appear in the following descrip-
tion, and the novel features thereof will be
particularly pointed out in the appended
claims.

In the drawings, Figure 1 is a side view of
a vehicle having a propeller constructed in
accordance with my invention. Fig. 2 is a
rear view, partly in section, of the same. Fig.
3 is a view of a sled-vehicle to which the pro-
peller embodying my invention is applied.
Fig. 4 is a partial plan view of the same, show-
ing the arrangement of parts when the pro-
peller-wheels are arranged foremost. Fig. 5
is a detail view of one of the wheel-spokes.

Similar numerals of reference indicate cor-
responding parts in all the figures of the draw-
ings.

1 designates a vehicle-body, which obvi-
ously may be of any suitable form and ca-
pacity, and mounted in suitable bearings
thereon is a driving-shaft 2, carrying propel-
ler-wheels, which may be either fast or loose
thereon. In the construction illustrated in
Figs. 1 and 2 the propeller-wheels are fast on
the shaft, and each consists of a hub 3, hav-
ing spaced parallel flanges 4 either integral
with or firmly attached to the hub, and a
plurality of longitudinally-flattened spokes
5, alternately attached at their inner ends to
the outer and inner flanges 4 and converging

outwardly to occupy positions in a common
longitudinal plane midway between the
planes of said flanges at intermediate points.
Said intermediate points of the spokes are 55
connected by an annular spacing-brace 6, ar-
ranged with its width in a longitudinal plane,
and beyond this brace the spokes are twisted
to form a quarter-turn and are extended to
constitute transversely-flat blades 7, adapted 60
to sink into a soft surface traversed by the
propeller and obtain a flat and efficient pur-
chase thereon. The longitudinally-flattened
body portions of the spokes facilitate the cut-
ting thereof through a soft surface, such as 65
snow, while the transversely-flattened or
blade portions are adapted to sink to a suffi-
cient depth to engage a firm or compact
stratum. Any desired number of spokes may
be employed, depending upon the diameter 70
of the wheel and the purpose for which it is
to be used; but in the construction illustrated
the body portions of the spokes have inward-
ly-converging side edges and are arranged
close together, whereby the terminals or blades 75
thereof are arranged at sufficiently short in-
tervals to insure the contact of a plurality
thereof at all times with the surface traversed.
Obviously this prevents an annoying jarring
of the vehicle when traversing a hard surface. 80
The extremities of the blades may have chisel
edges to facilitate the engagement thereof
with ice-surfaces.

As above indicated, any suitable construc-
tion of vehicle-body may be employed, and in 85
the same way any preferred means may be
employed for imparting rotary motion to the
propeller-wheels.

In the construction illustrated in Fig. 2
the motor, which is indicated in diagram at 90
8, communicates motion through a gear 9 to
a pinion 10 on the shaft. Also in this form
of the apparatus the support for the opposite
or front end of the vehicle-body consists of
steering-wheels 11, of which the pivotal axle 95
12 is connected, by chains 13 or otherwise,
with a steering-shaft 14. On the other hand,
in the construction illustrated in Figs. 3
and 4 the propeller-wheel shaft, which is
mounted above the plane of the sled top or 100
body 1^a carries propeller-wheels which are
loosely mounted thereon, connection be-

tween the shaft and the wheels being secured by means of clutches 15, having operating levers or handles 16, whereby the operator is enabled to disconnect either propeller-wheel 5 from the shaft, and thus allow the same to turn idly, while motion is communicated to the vehicle by the other wheel, and thus causes it to describe a curved path, as in turning, &c. In this construction the propeller-wheels 10 are preferably arranged at the front of the vehicle, and the other end thereof is supported by means of sled-runners 17. Any suitable mechanism may be employed for communicating motion to the propeller-shaft, and 15 therefore it has been deemed unnecessary to illustrate such mechanism in the form of the apparatus shown in Figs. 3 and 4.

Various changes in the form, proportion, and the minor details of construction may be 20 resorted to without departing from the spirit or sacrificing any of the advantages of this invention.

Having described my invention, what I claim is—

25 1. A rotary vehicle-propeller consisting of a rimless wheel having spokes arranged at their inner ends upon parallel spaced lines, converging outwardly to intersect in a common longitudinal plane, and extended beyond

said point of intersection to form transversely- 30 flattened blades, substantially as specified.

2. A rotary vehicle-propeller consisting of a rimless wheel having longitudinally-flattened spokes arranged at their inner ends upon parallel spaced lines, converging outwardly to intersect in a common longitudinal plane, and extended and twisted axially beyond 35 said point of intersection to form transversely- flattened blades, substantially as specified. 40

3. A rotary vehicle-propeller, having a flanged hub, outwardly-convergent longitudinally-flattened spokes secured at their inner ends alternately to the inner and outer flanges of the hub, and intersecting in a common longitudinal plane, and a spacing-brace connecting the spokes at their points of intersection, said spokes being extended beyond the spacing-brace and turned or twisted axially to form transversely-flattened blades, 45 substantially as specified. 50

In testimony that I claim the foregoing as my own I have hereto affixed my signature in the presence of two witnesses.

JOHN F. VENNER.
